BY *Victor J. Evans* INVENTOR

ATTORNEY

UNITED STATES PATENT OFFICE.

MARGARETTA STEVENSON, OF HAILEY, IDAHO.

WASHING MACHINE.

Application filed April 30, 1920. Serial No. 377,899.

To all whom it may concern:

Be it known that I, MARGARETTA STEVENSON, a citizen of the United States, residing at Hailey, in the county of Blaine and State 5 of Idaho, have invented new and useful Improvements in Washing Machines, of which the following is a specification.

This invention has reference to improvements in washing machines and resides in 10 the construction, combination and operative arrangement of parts set forth in the following description and falling within the scope of what is claimed.

The primary object of the invention is to 15 produce a simple construction of washing machine whereby the dasher may be turned at a minimum amount of physical exertion; whereby the said dasher may be readily removed when the clothes are to be arranged 20 in or removed from the body of the machine; whereby the dasher is supported in such a manner as to effectively retain the closure on the body of the machine; to produce a body of such shape and interior construction as to permit of the dasher properly 25 operating on the clothes to thoroughly clean every article thereof, and to further provide a construction whereby all of the water may be drained expeditiously therefrom.

30 Other objects and advantages will appear as the nature of the invention is better understood, reference being had to the accompanying drawings, in which:

Figure 1 is a side elevation of a washing 35 machine constructed in accordance with this invention.

Figure 2 is a top plan view thereof.

Figure 3 is a sectional view approximately 40 on the line 3—3 of Figure 1.

Figure 4 is a sectional view approximately on the line 4—4 of Figure 1.

Figure 5 is a top plan view with the dasher and supporting bracket therefor removed, the closure being also removed.

45 Figure 6 is a plan view of the sectional cover.

The body of the improvement, indicated by the numeral 10, is preferably constructed of metal, and both the sides and ends thereof 50 are rounded outwardly from their edges to the center thereof, the edges of the said sides and ends being preferably rounded toward each other and secured in any desired or preferred manner to provide a watertight joint therebetween. On the flat 55 upper end of the body is secured a plate 12

which provides the top of the body. The plate is centrally formed with a round opening and is preferably projected a suitable distance outward of the body. The plate, 60 at the rear thereof has an upstanding flange 13, the latter having its ends provided with side members 14 which are arranged at an inward inclination and terminate with the edge of the round opening 14' in the top. 65

Preferably the top portion within the flanges 13 and 14 is inclined in the direction of the opening 14', so that water from a wringer (not shown) which is supported upon the flange or plate 13 will be directed 70 through the said opening 14' into the body.

The body may have its inner face ribbed or corrugated, and the sides and ends of the body, at the bottom thereof have secured thereon a bottom plate 15 which is preferably dished to the center thereof. The body has secured thereon supporting legs 17 which have their outer ends provided with rollers 18 whereby the device may be readily wheeled to desired positions in the laundry. 80 The bottom is provided with an outlet spout 19 controlled by a suitable cock 20. The bottom may have its inner face ribbed or corrugated.

The opening 14' is normally closed by a 85 two-part door or closure 21, the confronting or meeting edges of the sections thereof having each a central semi-cylindrical notch 22. Also, if desired, the sections may be hinged at one of the ends thereof. 90

The bracket or standard that carries the working parts of the machine is broadly indicated by the numeral 23. This member includes a straight upper portion 24 having three depending tripodal legs. Each of the 95 legs is provided with an angle or straight portion forming a foot 25. Two of the legs 26 are arranged in alinement, while the remaining leg 27 is arranged at a right angle to a line extending through the legs 26. The 100 foot portions of the legs 26 are provided with slots 28, and the top plate of the body has headed turnable members 29 thereon. These members are designed to be received through the slots 28 and when given a half 105 turn are arranged transversely over the feet of the legs 26. The top plate of the body is provided with a slot 30, and the foot of the leg 27 is provided with a downturned portion in the nature of a tongue 31 that is 110 designed to be received in the slot 30.

On the side of the top diametrically op-

posite the slot 30 is a headed turnable member 32 which is designed to engage with the cover, the same being also engaged by the foot portions of the legs of the bracket or standard.

Through the registering semi-cylindrical openings in the confronting edges of the cover passes a shaft 33. This shaft has a lower portion which is substantially triangular in cross section, and to the sides of this triangular portion is secured a plurality of spaced outwardly extending dasher arms 34. The shaft is mounted in suitable bearings in the upper and straight portion of the bracket or standard and has secured thereon a toothed wheel 35. Journalized on the said upper portion of the bracket or standard is a short shaft 36 on one end of which is secured a comparatively large wheel 37, the same having peripheral equally spaced depressions or openings 38 to engage with the teeth of the wheel 37. It is, of course, obvious that two beveled wheels may be employed if desired. On the larger wheel is an operating handle 39.

By partly removing the standard or bracket the sectional cover may be removed from the top of the device, the said cover, as heretofore inferred, being effectively clamped by the bracket and by the turntable member 32 on the top of the body. When the cover is removed the standard and the shaft and dasher carried thereby may be entirely removed from the body, and it is thought, from the foregoing description, when taken in connection with the drawings, that the construction and advantages of the improvement will be apparent. It should be stated, however, that if desired the operating

wheel may have arranged thereon a pulley 40 that may receive the belt of a suitable motor so that the machine may be motor-driven if desired.

Having thus described the invention, what is claimed as new, is: —

1. The combination of a top plate having an opening and also having a slot spaced from said opening, a turn button connected to the top plate and arranged at the opposite side of the opening to said slot, headed turnable members connected to the top plate and arranged at opposite sides of said opening, a removable closure for said opening and having a central shaft-receiving opening, a shaft extending through said central opening, and a bracket receiving and supporting said shaft and having a leg with a horizontal portion to rest partly on the top and partly on the closure and terminating in a pendent portion to rest in the top slot and also having legs with slotted horizontal portions to rest partly on the top and partly on the closure and receive and be detachably secured by the said turnable members.

2. The combination of a top plate having an opening, closure means removably arranged in said opening and having a central shaft-receiving opening, a shaft extending through said central opening, and a bracket disposed above the top plate and supporting the shaft and having legs detachably connected to the top plate and also having portions of said legs resting over the closure means to hold the latter against displacement.

In testimony whereof I affix my signature.
MARGARETTA STEVENSON.
